UNITED STATES PATENT OFFICE.

ALBERT CHAMPION, OF FLINT, MICHIGAN, ASSIGNOR TO A C SPARK PLUG COMPANY, OF FLINT, MICHIGAN, A CORPORATION OF MICHIGAN.

TERMINAL CONNECTER FOR SPARK PLUGS.

Application filed October 28, 1921. Serial No. 511,131.

My invention relates to terminal connectors designed for use with electric supply conductors for connecting the conductor or cable to a device to which electricity is to be supplied, and particularly to connectors or terminals designed for use in connection with the ignition systems of internal combustion engines to connect the conductors through which electricity is supplied to the 10 spark plugs of the engine to the said plugs.

The principal object of my invention is to provide an improved terminal connector which is readily attachable to and detachable from the inner insulated electrode of the 15 spark plug to which current is supplied, and which is yieldably held in engagement with the said electrode.

A further object of my invention is to provide an improved connector for electric supply cables which is simple in construction and which may be readily and cheaply manufactured at a minimum of expense, and which may be readily attached to and detached from the plug electrode with which it 25 is connected.

With the above and other objects of invention in view, my invention consists in the improved terminal for electric supply conductors illustrated in the accompanying 30 drawing and hereinafter described and claimed; it being appreciated, however, that the drawing is for illustrative purposes only, and that my invention includes such variations and modifications of the particular embodiment thereof illustrated as come within 35 the scope of the concluding claims.

Referring now to the drawing wherein the preferred embodiment of my invention is illustrated:

40 Figure 1 is a view showing my improved connecting terminal in perspective, and connected with the central electrode of a spark plug.

Figure 2 is a view showing the terminal as 45 seen from a position below the same, considering the connector in the position in which it is shown in Figure 1.

Figure 3 is a view showing a slightly modified form of connector in section upon a 50 central plane extending longitudinally thereof.

Figure 4 is a similar central sectional view showing my improved terminal connector modified as to some of the features thereof.

Figure 5 is a view showing the connector 55 shown in Figure 4 as seen from beneath the same.

Figure 6 is a view showing a connector similar to that shown in Figures 1 and 2 but in which a modified plan is employed for 60 forming a connection between the conducting core of the cable and the terminal.

Figure 7 is a view showing my improved connector as comprising two principal parts, instead of one as in the other views. 65

Referring to the drawing, and first to Figures 1 and 2 thereof, my improved terminal connector is there shown as formed from a single sheet metal blank of proper 70 form bent and shaped to provide a body portion 7 adapted to fit about the insulating covering 8 of the supply cable through which a current of electricity is supplied to a spark plug 9 having a central insulated electrode which is provided with a head 10 at its upper end; and which blank is also provided with a portion which, after being properly bent and shaped, provides a cup-shaped 75 socket 11 which fits over the head of the central insulated electrode of the plug; the bottom of the socket being open to admit the head as shown.

It will be appreciated that in the form of my invention above referred to a single piece 80 blank of proper form is bent and shaped to provide the body portion 7 and socket 11, and that the portion 7 thereof is forced into holding engagement with the insulating covering 8 of the supply cable to thereby properly attach the connector as a whole to the 85 cable; the shaping of the blank and the attachment of the same to the supply conductor being accomplished by means of suitable

forming dies, presses, and equivalent implements which, however, form no part of the 90 invention to which this present application relates. The terminal shown is open along its under side at 12 where the edges thereof lie adjacent one another after the body portion has been forced into holding engagement with the insulating covering of the conductor; and said free edges may, if desired, be provided with interlocking elements, altho ordinarily the stiffness of the 95 material from which the connector is made 100

will be sufficient to insure a sufficiently firm attachment of the connector to the supply conductor. The body portion is provided 105

with a spur 13 cut free from the metal thereof and forced inward so that the point thereof will engage the conducting core 14 of the supply cable, which is ordinarily made up of 5 a considerable number of wires of small diameter, to thereby establish an electrical connection between the said core and the terminal connector as a whole.

The socket portion 11 of my improved terminal connector is hollow and of a size sufficient to receive the upper end or head 10 of the central electrode of the spark plug, as best shown in Figure 1, and said socket is provided adjacent its open side or end with 10 two oppositely disposed slots 14, 14 in the walls thereof, which are substantially parallel with the edge of the wall about the opening; and the reference numeral 15 designates a U-shaped holding member formed 15 from spring wire and the sides 16 of which lie within the slots 14 and are forced by the inherent resilience of said member into contact with narrow edge portions of the wall of the socket portion at the ends of the slots 20 aforesaid; so that, as clearly appears in Figure 2, the said sides, that is the sides of the U-shaped holding member, lie upon and extend across opposite sides of the interior of the socket. When the parts are assembled the resilient holding member is therefore, or may be, in a state of more or less initial stress acting to force the sides of the same against fixed stops provided by the 25 portions of the wall of the socket portion which are located at the ends of the slots in said socket portion. The free ends of the holding member 15 are bent inward as shown at 17, 17 to thereby hold the said holding member in permanent assembled relation 30 with the connector and the sides thereof within the slots 14, while at the same time permitting the said sides to move apart from one another as the conductor as a whole is forced over or removed from the enlarged 35 head 10 of the central electrode; which head has a shoulder 6 beneath which the sides 16 of the holding member lie when the connector is attached to the plug.

The head 10 fits quite loosely within the 40 socket 11 as mere contact between the parts, as distinguished from a joint in which the parts are held together by force, is sufficient in cases where a high tension current of electricity passes between the parts as in the 45 case in spark plugs. At the same time it will be appreciated that the terminal connector as a whole is prevented from becoming disengaged from the electrode by the side portions 16 of the U-shaped holding member 15 50 which lie beneath the shoulder 6 of the head 10; which side portions separate slightly as the connector is forced onto the head to connect the conductor with the plug, and when the same is pulled upward to disconnect the 55 conductor from the plug.

In the form of my invention shown in Figures 1 and 2, the terminal as a whole is held upon the supply cable by engagement between the body portion thereof and the exterior of the insulating covering of the 70 cable, while in Figure 3 the connector is provided with a contracted tubular portion 18 of small diameter which fits within the insulating covering 19 and through which the stranded conducting core 20 and the supply 75 cable extends; the free end of the said core being shown as passed through a hole in the socket portion 21 of the terminal and soldered to the metallic wall of said socket at the upper end thereof, as shown at 22 in 80 Figure 2. The socket 21 is otherwise the same as the socket 11 hereinbefore referred to, and the connector as a whole is held in place relative to the head 10 of the insulated plug electrode by a resilient holding member 85 15, the same as in Figures 1 and 2.

Figures 4 and 5 illustrate a form of my invention in which the connector receives the stranded conducting core 23 of the supply cable and fits within the insulating cover 90 24 thereof, the same as in Figure 3, but in which engagement between the walls of the connector and the insulating covering and core is relied upon to hold the connector in place and to establish an electrical connection 95 between the core and connector. Also, in this form of my invention, the socket portion 26 of the terminal is provided with a separate annular supporting member 27 which is secured in place within the open 100 lower end of the socket by inturned ledges 28, or otherwise; and which supporting member serves as a support for a resilient U-shaped spring member 29 similar to the holding member 15 and the sides 30 of which 105 extend across the opening in the lower end of the socket 26 and in the supporting ring 27, so that said sides may spread and pass over the enlarged head of the plug electrode as the connector is connected therewith or 110 detached therefrom as hereinbefore explained at length. In this form of my invention it will be seen that the resilient holding member which prevents the connector from becoming disengaged from the plug 115 120 electrode is supported by the annular supporting member 27 and is located entirely within the socket portion 26, whereas in the forms of my invention shown in the other figures portions of this resilient holding member lie outside the socket. The resilient holding member is held in proper relation to the supporting member and to the interior of the socket by holding lugs 31 formed integrally with said holding ring 27 and extending upwardly and over the holding member 29, and acting to hold the same in place, as clearly shown in Figure 4 of the drawing.

In the form of my invention illustrated in 130

Figure 6 a different scheme is provided for establishing an electrical connection between the stranded conducting core 32 of the supply cable and the terminal connector, such connection being provided by removing the insulating covering 33 adjacent the extremity of the core wires and folding said wires backward, as shown at 34, over the surface of the insulating covering; whereupon and as the body portion 35 of the connector is forced into engagement with the said covering in assembling the parts electrical contact will be established between the core wires and the connector because of the resulting contact between the parts. In this form of my invention the socket portion 36 and resilient securing member 37 are shown as similar to the socket 11 and holding member 15, altho it will be appreciated that the internally located form of resilient holding member illustrated in Figures 4 and 5 may be employed as preferred.

It will be appreciated that in all the forms of my invention hereinbefore described the terminal connector is made from a sheet metal blank of proper form which is shaped by the use of suitable dies so as to provide the socket and body portions thereof, the connector as a whole being one which may be made entirely by stamping and bending processes and one in which no machine work is necessary; from which it follows that the cost thereof will be reduced to a minimum and that the same, being made from sheet metal which is tough material, will be not likely to become broken when in use. At the same time the connector as a whole while fitting loosely upon the head of the central electrode of the plug is nevertheless held in permanent engagement therewith by the resilient holding members 15 or 29, the action of which, however, is such that the connector as a whole may be readily connected with and disconnected from the plug.

While preferably made in a single piece my improved connector may be made of two pieces 38, 39 as shown in Figure 7; each piece being so shaped as to provide half the socket and half the body portion of the terminal. These two parts may be secured together in various ways as by tongues 40 at the edge of one which extend through loops 41 at the edge of the other; and the resilient holding member may obviously be either of the completely enclosed form shown in Figures 4 and 5, or of the form shown in Figures 1 to 3 wherein the said member may be put in place by merely spreading and passing it over the lower edge of the socket, and may be replaced by a new holding member if such a course becomes necessary or desirable.

Having thus described and explained my

invention, I claim and desire to secure by Letters Patent:

1. A terminal connector formed from sheet metal and comprising a tubular body portion adapted to be secured to a supply cable, and a socket portion integral with said body portion and arranged substantially at right angles thereto, and having an opening leading thereinto, and the plane of which opening is in a plane substantially parallel with the axis of said tubular body portion; a resilient U-shaped holding member arranged substantially parallel with the opening aforesaid, and the side portions of which extend across said opening at the sides thereof; and fixed stops carried by said socket portion and with which said side portions engage when the parts are assembled.

2. A terminal connector formed from sheet metal and comprising a tubular body portion and means for securing it to a supply cable, and a hollow socket portion integral with said body portion and arranged substantially at right angles thereto, and having an opening leading thereinto, said socket portion having two oppositely disposed slots located adjacent said opening and said opening being in a plane substantially parallel with the axis of said tubular body portion; a resilient holding member U-shaped in form and the sides of which lie within the slots aforesaid and extend across said opening at the sides thereof; the ends of said slots forming stops which are grasped by the side portions of said holding member to thereby hold the parts in assembled relation.

3. A terminal connector formed from sheet metal and comprising a tubular body portion and means for securing it to a supply cable, and a hollow socket portion integral with said body portion and arranged substantially at right angles thereto, and having an opening leading thereinto, said socket portion having two oppositely disposed slots located adjacent said opening and said opening being in a plane substantially parallel with the axis of said tubular body portion; a resilient holding member U-shaped in form and the sides of which lie within the slots aforesaid and extend across said opening at the sides thereof; the ends of said slots forming stops which are grasped by the side portions of said holding member to thereby hold the parts in assembled relation; the extremities of the sides of said U-shaped holding member being bent inward toward one another and adapted to engage the exterior wall of said socket to thereby hold said holding member in place.

In testimony whereof I affix my signature.

ALBERT CHAMPION.
